REFRIGERATING APPARATUS

Edwin A. Kucher, Oakwood, Ohio, assignor to
General Motors Corporation, Dayton, Ohio, a
corporation of Delaware

Application November 28, 1941, Serial No. 420,836

8 Claims. (Cl. 62—6)

This invention relates to refrigerating apparatus and more particularly to apparatus suitable for use in conditioning the air for a private home or the like.

One object of this invention is to provide an improved type of air conditioning unit suitable for mounting in the attic of a private home or the like.

Another object of this invention is to provide an air conditioning apparatus designed to condition 100% fresh air irrespective of outside air temperatures.

Still another object of this invention is to provide a system in which the capacity of the system may be adjusted in a manner so as not to sacrifice efficiency.

A further object of this invention is to eliminate the necessity for making a large number of different sized air conditioning units.

More particularly, it is an object of this invention to connect two or more similar refrigerating units in tandem when one unit alone would have insufficient capacity, and to provide improved means for controlling the units when arranged in tandem.

Further objects and advantages of the present invention will be apparent from the following description, reference being had to the accompanying drawings, wherein a preferred form of the present invention is clearly shown.

In the drawings:

Fig. 1 is a vertical sectional view somewhat diagrammatic showing a tandem air conditioning unit constructed in accordance with my invention and installed in a private home;

Fig. 2 is a perspective view intended to show the construction of the plenum chamber and the method of securing the plenum chamber to the main air conditioning unit;

Fig. 3 is a vertical sectional view taken on line 3—3 of Fig. 4 showing the general arrangement of a single unit;

Fig. 4 is a vertical sectional view taken on line 4—4 of Fig. 3; and

Fig. 5 is a sectional view largely diagrammatic showing the refrigeration circuits, the water circuits and the electrical circuits together with the principal controls.

Even though private homes require summer air conditioning just as badly as offices and other commercial establishments, very few homes have been equipped with summer air conditioning systems. One of the principal reasons for this is that the cost of an air conditioning system capable of conditioning the air for a private home has been prohibitive. One reason for this high cost has been that the most satisfactory prior art systems have required complicated and expensive air distributing ducts. Furthermore, the cost of operating the prior art systems has been excessive in comparison with the cost of operating

a system designed in accordance with my invention. Another reason for the high cost of the prior art air conditioning units is that different sized units have been required for different sized homes. It is obvious that the cost of manufacturing a given number of units is much greater if these units are not all the same size. By virtue of my improved construction, no air ducts are required and the necessity for manufacturing a large number of different sized home air conditioning units has been eliminated.

In Figs. 2, 3 and 4, I have shown a single air conditioning unit which may be placed in the attic of a home for conditioning the air for the home. The construction and arrangement of the unit is such that it may be used alone or it may be arranged in tandem with one or more similar units for conditioning the air for the home. Each unit comprises a main cabinet 10 which houses a refrigerant evaporator 12, a sealed motor-compressor-condenser unit 14 connected in refrigerant flow relationship with the evaporator 12, and a blower unit 16 driven by blower motor 18 through the belt 20. For a more detailed description of the motor-compressor-condenser unit 14, reference is hereby made to my co-pending application Serial Number 326,853, filed March 30, 1940, now Patent No. 2,286,491, issued June 16, 1942. Refrigerant vaporized in the evaporator 12 returns to the unit 14 through the line 15 and liquid refrigerant is supplied to the evaporator through the line 17. Reference numeral 19 designates a refrigerant control device which may be either a fixed restrictor or an expansion valve.

A plenum chamber 22, lined with insulating material 23, is arranged adjacent the blower outlet 24. This plenum chamber 22 is removably secured to the main cabinet 10 merely by hooking the flange 36 over the bracket 38 which is carried by the wall of the main cabinet 10. Stationary lugs 40 carried by the cabinet 10 cooperate with the notched flanges 42 on the plenum chamber 22 so as to removably hold the plenum chamber 22 in place once the chamber is lowered into place. A baffle 28 is provided within the plenum chamber for directing the flow of air within the chamber. An air outlet opening 30 is provided in the bottom wall of the plenum chamber, as shown in Fig. 2, through which the conditioned air is discharged downwardly into the conditioned space.

As shown in Fig. 1 wherein two of these units have been shown connected in tandem, the conditioned air is discharged into the upper hall from whence the air is distributed to the various rooms through the hallways. An air distributing plaque 32 is provided for directing the air substantially horizontally along the ceiling of the second floor hall. Since every house has a different arrangement of rooms, it is obvious that

the arrangement shown in Fig. 1 has been shown for purposes of illustration only and that the apparatus is equally applicable to one-story homes. It is also obvious that the conditioned air may be discharged into some room other than the hallway if desired. In the arrangement shown in Fig. 1, all of the air to be conditioned enters the attic space 34 through the attic window 35, and enters the cabinet 10 through the inlet 25. A filter 27 is provided adjacent the inlet 25.

When it is desired to provide an air conditioning system having a capacity greater than the capacity of a single unit, two units are connected in tandem, as shown in Figs. 1 and 5. When two units are connected in tandem, the conditioned air leaving the first plenum chamber discharges into the inlet 25 of the second cabinet 10 through an adapter 44. When two units are connected in tandem, a new outlet opening 46 is provided in the first plenum chamber, as shown in Fig. 5, through which the air discharges into the second unit.

Inasmuch as there are many localities in which the condenser cooling water is sufficiently cool to be usable in precooling the relatively hot incoming fresh air, each unit is designed so that a water coil 50 may be mounted ahead of the evaporator, as best shown in Figs. 3 and 5. When two units are connected in tandem, the water coil is omitted from the second unit since the air leaving the first evaporator would be cooler than any water normally available.

Referring now to Fig. 5 in which the water connections are shown, reference numeral 52 designates the main water supply line through which cooling water from any convenient source, such as the city water mains, is supplied. Pipe line 54 connects the air cooling coil 50 with the supply line 52. The water leaving the coil 50 is used for cooling the condenser of the first tandem unit and is supplied to the interior of the motor-compressor-condenser unit 14 of the first unit through the line 56. The water leaves this motor-compressor-condenser unit through the line 58 which connects to the water drain 60. The flow of water through the coil 50 and its associated motor-compressor-condenser unit 14 is controlled by means of a valve 62 which is regulated in response to the pressure within the condensing chamber, in accordance with well known practice. A small tube 64 connects the pressure operated valve 62 with the interior of the condensing chamber.

During light loads, only one of the tandem units is required to operate. When the capacity of the one unit is insufficient for properly cooling the air, a second unit is automatically placed into operation, as will be explained more fully hereinafter. When the second unit is in operation, water from the main supply line 52 flows directly to the condensing portion of the second motor-compressor-condenser unit 14 through the line 65. The water leaves the second unit 14 through the line 66 which also connects to the drain line 60. The flow of condenser cooling water through the second motor-compressor-condenser unit 14 is controlled by a valve 68 which is similar in construction and function to the valve 62. A small tube 70 connects the valve 68 with the condensing chamber of the unit 14. Each water control valve functions in its usual well known manner to close off the supply of condenser cooling water when no water is required. The tubes 64 and 70 are preferably at-

tached to pressure actuated bellows within the casings 14. A drain pipe 71 has been provided for carrying away the condensate from the condensate collecting pan 73.

Referring now to the electrical circuit shown in Fig. 5, reference numeral 80 designates the main power supply lines. Reference numeral 82 designates a switch which may be operated either manually or automatically so as to render the entire air conditioning system ineffective. Electrical energy is supplied to both of the blower motors 18 through the lines 84. A thermostat 86 located adjacent the inlet to the first unit, and which therefore responds to the temperature of the outside air, controls the operation of the switch 88 which renders both blowers ineffective when the outside temperature falls so low that the outside air is unsuitable for forced ventilation purposes. A manual switch 90 is provided in the circuit leading to the blower motor of the first unit and a corresponding manual switch 92 is located in the circuit leading to the blower motor 18 of the second unit so that either one or both of the blower motors may be stopped independently of the automatic control described hereinabove.

A switch 94 is provided in the circuit leading to the motor-compressor-condenser units 14. This switch may be controlled either manually or automatically. In order to simplify this disclosure, no automatic control has been shown for operating the switches 82 and 94, but it is within the purview of this invention to provide either a dry bulb thermostat, a wet bulb thermostat, or a combination of the two for controlling these switches. The controls may respond to the condition of the incoming air or to the condition of the air within the disclosure, or to both.

In order to prevent excessive loading of the electrical circuits, I have provided means for preventing both of the motor-compressor-condenser units from starting up at the same time. This means comprises a switch 96 which does not close until a predetermined time interval after the motor-compressor-condenser 14 of the first unit has been energized. The switch 96 is closed by means of the solenoid 98. A dash pot 100 has been provided for retarding the closing movement of the switch 96. Thus, upon energization of the solenoid 98, the switch 96 is biased to the closed position but does not move immediately to the closed position due to the retarding action of the dash pot 100. Since both units are not required to operate at all times, I have provided automatic means for rendering the second unit ineffective whenever the air conditioning load is such that the first unit has ample capacity. This means comprises a thermostat 102 located adjacent the inlet of the second unit. The thermostat 102 is adjusted so as to open the switch 104 whenever the temperature of the air leaving the first unit is sufficiently cool for discharging into the conditioned space. By virtue of this arrangement, both units normally operate when the outside air temperatures are so high that a single unit would have insufficient capacity to properly cool the air, and only the first unit operates when it alone has sufficient capacity to properly condition the air. Manual switches 105 make it possible to individually control each compressor unit.

In a system in which the major portion of the air is recirculated and the air is cooled to a temperature of 50° or 55° at the outlets, and the op-

erating back pressures in the refrigerating system, when using difluoro-dichloro methane as a refrigerant, are maintained between 30 and 38 pounds, approximately 30% of the work produced is recovered by recirculating the air. The thermal efficiency of such systems usually approximates 10 or 12 B. t. u. per watt input.

In a system constructed in accordance with my invention in which a greater amount of air is cooled and in which all of the air is fresh outside air, and in which the air is cooled to a temperature of 65° or 70° at the outlets, and the operating back pressures in the refrigerating system, when using difluoro-dichloro methane as a refrigerant, are maintained between 42 and 50 pounds, the thermal efficiency approximates 18 to 20 B. t. u. per watt input, whereby the relative increase in thermal efficiency more than compensates for the recovery in a recirculating system.

This thermal efficiency runs much higher in those installations in which the available cooling water may be used in precooling the relatively hot outside air. In fact, the thermal efficiency of such a system commonly runs as high as 23 B. t. u. per watt. By virtue of this fact, it is obvious that a small inexpensive system is provided which makes it possible to condition all fresh air at a very low cost.

The expression "self contained unit" is used to designate a unit in which a common support is provided for the compressor, condenser and evaporator and holds these elements in fixed relation at all times.

While the form of embodiment of the invention as herein disclosed, constitutes a preferred form, it is to be understood that other forms might be adopted, all coming within the scope of the claims which follow:

What is claimed is as follows:

1. Air conditioning apparatus comprising in combination, a first volatile refrigerant air conditioning unit, a second volatile refrigerant air conditioning unit, each of said units comprising an evaporator, a compressor and a condenser, means for circulating a stream of fresh air over said evaporators in series, a water coil arranged in said air stream, means for flowing water through said water coil and thereafter in thermal exchange with one of said condensers, and means for rendering one of said evaporators ineffective during light air conditioning loads, said last named means comprising a thermostatic means responsive to the temperature of the air leaving the first of said evaporators for controlling the flow of refrigerant through said second evaporator.

2. Air conditioning apparatus for conditioning the air in a private home or the like, comprising in combination, means for flowing a stream of outside air into the space to be conditioned, a first refrigerant system having an evaporator located in said air stream, a second refrigerant system having an evaporator located in said air stream, means responsive to the temperature of the air leaving said first evaporator for controlling the flow of refrigerant to said second evaporator.

3. Air conditioning apparatus for conditioning the air in a private home or the like, comprising in combination, means for flowing a stream of outside air into the space to be conditioned, a first refrigerant system having an evaporator located in said air stream, a second refrigerant system having an evaporator located in said air

stream, means responsive to the temperature of the air leaving said first evaporator for controlling the flow of refrigerant to said second evaporator, means for flowing water in thermal exchange with said air stream, and means utilizing said water for cooling a portion of one of said refrigerant systems.

4. Air conditioning apparatus for conditioning the air in a private home or the like comprising in combination, means for flowing a stream of air into the space to be conditioned, a first refrigerant system having an evaporator located in said air stream, a second refrigerant system having an evaporator located in said air stream, thermostatic means responsive to the temperature of the air flowing from said first evaporator to said second evaporator for controlling the cooling of air by said second evaporator.

5. Air conditioning apparatus for conditioning the air in a private home or the like, comprising in combination; a first self-contained air conditioning unit including an evaporator, a compressor, and a condenser; a second self-contained air conditioning unit comprising an evaporator, a compressor, and a condenser; means for directing air to be conditioned in thermal exchange with the evaporator of said first unit and thereafter in thermal exchange with the evaporator of said second unit; and means responsive to the temperature of the air leaving the evaporator of said first unit for controlling the cooling of air by said second evaporator.

6. Air conditioning apparatus for an enclosure comprising in combination, means for flowing a stream of outside air into the space to be conditioned, a first portable self-contained refrigerant system having an evaporator located in said air stream, a second portable self-contained refrigerant system having an evaporator located in said air stream, means responsive to the temperature of the air leaving said first evaporator for controlling the flow of refrigerant to said second evaporator, means for flowing water in thermal exchange with said air stream, and means utilizing said water for cooling a portion of one of said refrigerant systems.

7. Air conditioning apparatus for conditioning the air in a private home or the like comprising in combination, duct means for directing a stream of air into the space to be conditioned, a first refrigerant system having a blower and an evaporator located in said air stream, a second refrigerant system having a blower and an evaporator located in said air stream, thermostatic means responsive to the temperature of the air flowing from said first evaporator to said second evaporator for discontinuing the cooling of air by said second evaporators while maintaining operation of said second blower.

8. Air conditioning apparatus for conditioning the air for a private home or the like comprising in combination, duct means for directing a stream of air into the space to be conditioned, a first refrigerant evaporator and blower located in said air stream, a second refrigerant evaporator and blower located in said air stream, means for supplying refrigerant to said evaporators, thermostatic means responsive to the temperature of the air flowing from said first evaporator to said second evaporator for discontinuing the cooling of air by said second evaporator, and means responsive to the incoming air temperature controlling the operation of said blowers.
